MARKING DEVICE

Harry M. Smallen, Brooklyn, N. Y.

Application June 15, 1934, Serial No. 730,793

5 Claims. (Cl. 101—35)

My invention relates to improvements in printing or marking machines, and more particularly has reference to and is illustrated in the accompanying drawings in its application to a machine of the class described, which is in the nature of an improvement upon a similar machine set forth in my co-pending patent application Serial Number 710,861. In my previous application, I did not make provision for the tapered sides of the loaf of bread, the loaf being usually wider at the top than at the bottom, the baking pans being so made for easy discharge of the loaves. In the present application, I have made due provision for this, as will be found hereinafter.

Referring to the drawings, Fig. 1 illustrates, in end elevation, a suitable form of marking device embodying an application of my invention. Fig. 2 is a view looking from right to left thereof, partly in section, and Fig. 3 is a plan view.

4 indicates the base or platform of the machine, upon which the branding wheels 5, 6 are carried upon the carriages 7, 8 provided with wheels 9, 10, adapted to roll upon tracks 11, 12. The branding wheels are mounted upon vertical shafts 13, 14, having sprockets 15, 16 connected with sprocket chain 17, which passes over the tension idler 18, upon shaft 19, resiliently projected as indicated at 20 to take up slack. 22 indicates a loaf of bread upon the conveyor 23, passing over roller 24, between the branding elements 5, 6.

25, 26 are frames, in the top or the yoke of which are mounted the branding wheel shafts such as 13, 14, the said shafts passing through the supports such as 27, 28, into which the ends of the frames 25, 26 are secured as indicated at 29, 30, and from opposite sides or ends of said frames project studs 31, 32, having bearings in the blocks 33, 34, slidably adjustable in the standards 35, 36 by screws such as 37, 38, said standards being secured as shown. The free ends of the inverted U-shaped frames 25, 26 are slidably adjustable in the slots 39, 40 and 41, 42, and are secured in adjusted position therein by the set-screws 29, 30, or by other suitable means. The supports or platforms 27, 28, in addition to being secured to the U-shaped frames 25, 26, are suspended at their outer sides by springs 44, hanging from standards 45, upon platforms 7 and 8, thus allowing the marking surfaces or peripheries of the marking wheels 5, 6, which may be normally in a vertical plane, to adjust themselves at an angle thereto conforming to the taper of the sides of the bread being marked, the marking

pressure being at all times provided by the springs 46.

Of course it will be understood that various modifications may be made in the construction and arrangement of parts, without departing from the spirit of the invention as claimed.

I claim:

1. In a machine of the class described, marking means, and in combination therewith, means for allowing said means to rotate upon axes in a plane parallel to the line of travel of the article being marked, said means located at opposite sides of said article, and resilient means for automatically maintaining a predetermined angle of contact between said marking means and said article.

2. In a machine of the class described, marking means, and in combination therewith, means for allowing said means to rotate upon an axis in a plane parallel to the line of travel of the article being marked, and means for maintaining synchronization of said marking means in relation to varying angles of the surfaces being marked.

3. In a machine of the class described, marking means, and in combination therewith, means for allowing said means to rotate upon an axis in a plane parallel to the line of travel of the article being marked, and means for independently and automatically synchronizing the adjustment of said marking means relative to variations in the plane of the surfaces to be marked.

4. In a machine of the class described, marking means, and in combination therewith, means for allowing said means to rotate upon axes in a plane parallel to the line of travel of the article being marked, and means for maintaining synchronization of said marking means in relation to varying angles of the surfaces being marked, means for maintaining synchronous operation between marking means at opposite sides of the article to be marked.

5. In a machine of the class described, marking means, and in combination therewith, means for allowing said means to rotate upon axes in a plane parallel to the line of travel of the article being marked, and means for maintaining synchronization of said marking means in relation to varying angles of the surfaces being marked, means for maintaining synchronous operation between marking means at opposite sides of the article to be marked, for maintaining synchronous action between said last mentioned means and said automatic angle of adjustment means.

HARRY M. SMALLEN.
